UNITED STATES PATENT OFFICE.

JOHN E. FULLER, OF HARTSVILLE, SOUTH CAROLINA.

HYDROCARBON ENGINE.

Application filed January 18, 1928. Serial No. 81,957.

This invention relates to a fuel injection device for internal combustion engines, and it is in some respects an improvement on my application Serial No. 595,502, filed October 5 19, 1922. One of the objects of my present invention is to thoroughly mix the air and fuel used in a hydro-carbon motor, which object is attained, in part, by spraying the fuel across the path of the incoming air. An 10 other object is to vaporize a considerable part, if not all, of the fuel, and this is accomplished by hurling the fuel in the form of a spray against a hot surface, in the present case the exhaust valve. Another object 15 is to heat the incoming air. This is done by conducting the air across a hot surface, in the present case the exhaust valve, thus not only heating the air but conserving the valve by reducing its temperature. The air is con- 20 ducted across the exhaust valve by means of a deflecting vane or baffle, which imparts a circular or whirling motion to the air, i. e., the mixture of air and fuel, as it passes to the cylinder, thus more thoroughly mixing the 25 air and fuel. Other objects, and novel means for attaining them, will be described presently.

In the accompanying drawings, which illustrate one embodiment of my invention,

30 Fig. 1 is an elevational view, partly in section on line 1—1 in Fig. 2, of a portion of an internal combustion engine equipped with my fuel injection device;

35 Fig. 2 is a fragmental sectional plan view of the combustion chamber of one cylinder of my engine, taken on the line 2—2 of Fig. 3, showing the deflecting vane or baffle and its relation to the cylinder, the exhaust and intake valves;

40 Fig. 3 is a fragmental sectional view on line 3—3 in Fig. 2;

Fig. 4 is a section thru the fuel injection valve on line 4—4 in Fig. 1;

45 Fig. 5 is a section on the line 5—5 in Fig. 4, but with the valve plug rotated 90 degrees;

Fig. 6 is a bottom view of what, for the want of a better name, I shall call a dia- phragm, drawn on a larger scale than the other views; and

50 Fig. 7 is a sectional view of the fuel nozzle, also drawn on an enlarged scale.

In the drawings the various parts are shown in positions best adapted to exhibit the parts, and it is not to be understood that the engine is to be operated with the parts 55 in the relative positions they occupy in the

drawings. In fact, the proper positions of the parts will depend upon conditions; for example, the number of cylinders there are in the engine. In view of the following description of my invention and its relation to the engine as a whole, which engine is in the main of a well known type, anyone skilled in the art to which my invention appertains will understand how to time the various move- 60 65 ments.

Referring now to the drawings, 10 is a cylinder block of an internal combustion engine. One of the cylinders in this block is shown in Fig. 3 and is designated by the numeral 11; 12 is the piston for this cylinder. While the drawings illustrate only one cylinder, it is to be understood that my invention is applicable to engines of various numbers of cylinders. 70 75

Situated in a lateral extension 15 of the cylinder block 10 are an air inlet valve 13 and an exhaust valve 14, arranged to move vertically in guides 16, the former closing an air port 17 and the latter closing an exhaust port 18. Below this extension is a cam shaft 19 revolvable in bearings 20, only one of which is visible in Fig. 1. Cams 21 and 22 on this shaft operates valves 13 and 14 thru the medium of followers 23 and 24, 80 85 respectively. The valves are closed by compression springs 25 and 26. Air enters the port 17 thru a manifold 27, and the exhaust gases leave the port 18 thru a manifold 28. It is to be understood that, as the name im- 90 plies, the intake and the exhaust manifolds serve other cylinders of the engine. 95

A cylinder head 29 covers the cylinder block 10 and is constructed so as to provide a combustion chamber 30 above each cylinder. This cylinder head also covers the extension 15 of the block and the combustion chambers 30 extend into the portions of the head 29 which cover the valves 13 and 14. Thus the engine is similar to the well known "L" head 100 type of engine.

Referring now to Fig. 2 it will be seen that the valves 13 and 14 are side by side and equal distances from the center of the cylinder 11. Extending from the side of the combustion chamber adjacent to the inlet valve 13, a deflecting vane or baffle 31 is interposed between the valve and cylinder. This vane forces the incoming air to pass across the exhaust valve 14, which heats the air and cools 110 the valve. The air then encounters the curved wall of the chamber adjacent to the

exhaust valve, whereby its direction is changed and the air is caused to move in a circular path and enter the cylinder with a whirling motion.

5 I shall now describe my fuel injection system, referring first to Fig. 1. A fuel injection valve is screwed into the cylinder head 29 directly above the exhaust valve 14. This valve comprises a casing 40 carrying a 10 tapered plug 42, which has cylindrical projections 43 and 44 extending axially from its tapered body. The projection 44 carries a collar 45. A compression spring 46 surrounding the extension 44 and confined between the 15 collar 45 and a thrust bearing 47 resting against the casing 40, keeps the plug 42 firmly seated in the casing 40. The plug is bored to provide an axial passage 50; holes 51 connect this passage with the surface of the plug. 20 The purpose of these holes will be explained later.

A similar valve is provided for each cylinder of the engine; in Fig. 1, two such valves are shown. Adjacent valves are connected by 25 hollow flexible couplings 60. The first plug in the series is connected by a similar coupling to a shaft 61, mounted in a bearing 62 carried by one end of the cylinder head 29. The shaft 61 is rotated by and in synchronism 30 with the cam shaft 19 of the motor by a sprocket chain, only a portion of which is shown. The shaft 61 is drilled from one end to form a passage 63. A port 64 connects this passage to an annular recess 65 in the bearing 35 62, which recess is connected to an oil supply by a pipe 66. The projection 44 on the last plug in the series rotates in a stationary cap 67, having an outlet 68 which may be varied by a valve 69. All the plugs 42 are 40 cooled by oil, which flows thru the shaft 63, plugs 42 and couplings 60 under pressure. By throttling the flow of oil with the valve 69, the pressure may be increased sufficiently to 45 force oil thru the holes 51 to lubricate the valves. It is deemed unnecessary to illustrate or describe means for producing this flow of oil.

The several plugs in the series are coupled together in their proper angular relationship, 50 while the flexible couplings prevent lateral thrusts on the plugs, should the casings 40 become slightly out of alignment thru unequal expansion, or for other reasons.

Referring again to Fig. 1 it will be seen 55 that passing transversely thru the center of each plug 42, and intersecting its axis are two parallel tubes 70, one of which is to receive, fuel, and both of which are connected to a supply of air or gas under pressure at certain parts of the operating cycle, as will be 60 further explained presently. Traversing the casing 40, from end to end, are two passages 71. When the plug is in the position shown in Figs. 1 and 4 the tubes 70 register 65 with the passages 71, forming two contin-

uous passages thru the casing. Secured to the bottom of the casing is what I shall call, for want of a better name, a diaphragm, 72, having two passages 73 which register with the passages 71 in the casing. On the bottom 70 of this diaphragm is a centrally located conical point 74. The passages 73 open on opposite sides of the base of this cone, see Fig. 6. Referring to this figure it will be noticed that passages 73 traverse the diaphragm obliquely, their inclinations being in opposite directions. Further reference to this will be made presently. A circular plate 75 is placed on an annular sill in the bottom of the tapped hole into which the casing 40 is afterward 80 screwed. This plate is traversed by a passage consisting of a conical or funnel-shaped recess 76, which extends about three-fourths of the way thru the plate, where it joins an inverted conical or funnel-shaped bore 77. 85 The juncture of these two conical bores forms an orifice 78, constituting the outlet of the nozzle. The diaphragm 72 comes to rest on the plate 75 when the casing is screwed in, the cone 74 extending into the recess 76. But 90 the cone being considerably smaller than the recess, there is formed a conico-annular passage or mixing chamber 79 (see Figs. 1 and 4) into which the oblique passages 73 open. 95

Fuel is supplied to the plug 42 of the injection valve thru a pipe 80, communicating with a recess 81 in the bore of the casing 40. See Figs. 4 and 5. A valve 82 in the pipe 80 is provided to regulate the quantity of fuel supplied. On the opposite side of the bore 100 is a recess 83, similar to recess 81, which recess is connected thru a pipe 84 to a vent pipe 85, common to all the injection valves on the engine, which pipe is connected to the intake manifold 27 thru a valve 86. Leading from each cylinder, or its combustion chamber, to the top of the injection valve of the cylinder in next firing sequence, is a pipe 87.

I shall now describe the operation of my fuel injection system: when the valve plug 110 42 is in the position shown in Fig. 5, one of the tubes or passages 70 connects the recesses 81 and 83, enabling fuel to flow from the pipe 80 to said passage 70. This flow of fuel is stimulated by the relatively low pressure in the recess 83, due to its being in communication with the manifold 27. In effect the supply of fuel is under pressure. As the plug is rotating continuously the duration of this connection depends upon the length of said recesses. If it ever became desirable to admit fuel to both tubes 70 it would be possible to do so by merely lengthening the recesses 81 and 83, so as to allow the ends of both tubes 70 to register with the recesses simultaneously. Such a modification is so obvious that it is deemed unnecessary to illustrate it. The movement of the plug 42 is so timed that it reaches the position shown in Figs. 1 and 4, wherein the passages 70 and 71 register, at a 120 125 130

time when the content of the cylinder to which the passages are connected (by a pipe 87) is highly compressed. A small portion of the content of this cylinder, passing thru the pipe 87 to the valve casing, blows the fuel contained in the passage 70 thru one of the passages 71 and the corresponding oblique passage 73, into the conico-annular passage or mixing chamber 79, where, because of its entrance obliquely, the fuel is made to traverse a volute path toward the orifice 78, resulting in its emergence from the nozzle in a whirling spray. At the same time a portion of the content of said cylinder enters the mixing chamber 79 thru the other passages 70 and 71, and becomes mixed with the charge of fuel. This mixture is ejected from the nozzle with such force that it is hurled against the hot exhaust valve 14, in spite of the cross current of air which it encounters in the combustion chamber. The fuel is vaporized by contact with the exhaust valve, and being picked up by the current of air, which is also heated by the exhaust valve, the air and fuel are further mixed by the whirling motion imparted to it by the deflecting vane 31. Upon the compression stroke of the piston the fuel mixture is driven back into the combustion chamber, the vane 31 now imparting to the mixture a whirling motion in the opposite direction. This insures a thorough mixing of the air and fuel, also complete vaporization of the fuel, resulting in nearly if not quite perfect combustion. The exhaust valve is kept from becoming injuriously hot by this periodical flow of fresh air across it.

I provide two means for regulating the quantity of fuel supplied to the passages or reservoirs 70 in the valve plug. First, each fuel pipe 80 is provided with a regulating valve 82 to control the quantity of fuel flowing to its passages 70. Second, a valve 86 in the common vent pipe 85 regulates the effectiveness of the vent and thereby controls the quantity of fuel that flows into all of the valve plugs. For example, for various reasons, such as slight inaccuracies in the parts or in their respective timing, a larger or smaller quantity of fuel may tend to enter the passage 70 in one plug than in other plugs. This can be corrected by adjustment of the several valves 82. After these valves have been adjusted so that with a given vacuum in the pipe 85 each cylinder receives the same quantity of fuel, the quantity of fuel delivered to the several cylinders may be varied by adjustment of the valve 86. Thus the richness of the fuel mixture may be adjusted with the single valve 86. As will be obvious, in no case is sufficient fuel admitted to the reservoirs or antechambers 70 to permit fuel to overflow into the vent 83, for this would be a waste of fuel. Neither the flexible couplings nor the cooling system described are essential to the operation of my device, altho both serve useful purposes. Nor is it essential that the injection blast be obtained from another cylinder, as an independent source of compressed gas could be used. In such a case my injection valve could be used on a single cylinder engine.

In practice of my invention it is not essential that there be two passages 70 and 71, as one may be dispensed with. Two oblique passages 73 are advantageous for the purpose of producing the whirling spray issuing from the nozzle 77, but a single passage 71 might be arranged to connect to both passages 73, and this, being suggested, is sufficiently obvious to not require illustration. One of the spiral passages 73 might even be dispensed with, altho at some sacrifice of efficiency, depending, among other things, upon the character of the fuel used.

It is not to be understood that the deflecting vane is applicable only to a case wherein the air and fuel enter the combustion chamber separately, it being clear that the vane would operate in the manner described were the valve 13 used to admit a mixture of air and fuel instead of air alone.

While I have illustrated and described but one embodiment of my invention it is not to be understood that it is limited to the construction shown. The scope of my invention is measured by the appended claims:

I claim:

1. In a fuel injection device for an internal combustion engine, a valve comprising a plug revolvable in a casing, said plug having a passage through it perpendicular to its axis of rotation, and having a relatively large longitudinal passage; said first mentioned passage comprising a tube which crosses the longitudinal passage, but enough smaller in diameter to avoid obstructing the latter, and means for introducing fuel to said tube and lubricant to said longitudinal passage.
2. In an internal combustion engine having a plurality of cylinders, a valve on each cylinder having a tapered plug revolvable in a casing, the several plugs being in axial alinement and connected to rotate as an integer, said connection permitting each plug to seat itself in its own casing independently of the other plugs; said plugs having longitudinal passages which, being connected, permit a flow of liquid through the series whereby to cool the valve each plug having a hole leading from said passage to its exterior, through which a portion of the liquid traversing the series of plugs may emerge to lubricate the plugs.
3. In an internal combustion engine having a plurality of cylinders served by an intake manifold, an injection valve for each cylinder comprising a casing having a fuel supply passage and a vent, a valve plug movable in each casing and provided with a fuel reservoir adapted to receive fuel when in

registration with the fuel supply passage and vent, a pipe connecting the vent in each casting to a common pipe leading to said manifold, and a valve in said common pipe whereby to control the vacuum and thus vary the quantity of fuel drawn into the reservoirs.

4. In an internal combustion engine having a plurality of cylinders served by an intake manifold, an injection valve for each cylinder comprising a casing having a fuel supply passage and a vent, a valve plug movable in each casing and provided with a fuel reservoir adapted to receive fuel when in registration with the fuel supply passage and vent, a pipe connecting the vent in each casing to a common pipe leading to said manifold, a valve in said common pipe whereby to control the vacuum and thus vary the quantity of fuel drawn into the reservoirs, and a separate valve for each fuel supply passage, whereby to equalize the quantity of fuel admitted to the several injection valves.

5. In an internal combustion engine having a plurality of cylinders, a plurality of fuel injection valves, each having a casing provided with a fuel supply passage and injection blast passages, each valve being also provided with a fuel chamber and a mixing chamber, and a separate conduit from the combustion chamber of each cylinder to the fuel injection valve for the cylinder next in firing sequence, for conveying injection gas pressure to said injection blast passages.

6. In an internal combustion engine having a plurality of cylinders, a plurality of fuel injection valves, each comprising a valve casing, a valve plug revoluble therein, said casing and plug being provided with fuel and injection blast passages, and a separate conduit from the combustion chamber of each cylinder to the fuel injection valve for the cylinder next in firing sequence, providing means for supplying gases under pressure for atomizing and injecting the fuel in accordance with the firing sequence of the cylinders.

7. In a fuel injection device for internal combustion engines, a valve comprising a rotary plug in a casing, said rotary plug and casing having two passages therethrough, said passages intersecting the axis of rotation at right angles and leading to a mixing chamber and spray nozzle, said casing having an additional passage and vent, the former for conveying liquid fuel to one of said passages in the rotary plug, and means for supplying injection blast pressure to both passages for the purpose of atomizing and injecting the fuel.

8. In a fuel injection device for internal combustion engines, a fuel supply passage, an antechamber, means for transferring fuel one charge at a time from said passage to said

antechamber, a vent for the antechamber, a throttling valve in said vent for regulating the quantity of fuel entering the antechamber, means for subjecting the fuel in the antechamber to pressure whereby to expel said fuel therefrom, and means for closing the vent during that time.

9. In a fuel injection device for internal combustion engines, a valve casing, a rotary valve plug, a fuel supply passage in said valve casing, a fuel chamber in the valve plug, a vent in the valve casing, and a throttling valve in the vent to facilitate regulation of fuel entering said fuel chamber in the valve plug.

10. In an internal combustion engine having a plurality of cylinders, a plurality of fuel injection valves, each comprising a casing with a fuel supply passage and a vent, a valve plug movable in each casing and provided with a fuel reservoir adapted to receive fuel when in registration with the said fuel supply passage and vent, a common vent pipe connecting the vent on each casing, a throttling valve in said common vent pipe to facilitate uniform and regulated feeding of fuel to each of the several fuel injection valves.

11. In an internal combustion engine having a cylinder, an air passage to the cylinder, a rotary plug injection valve having a fuel passage in the plug, fuel supply and vent passages to said plug, two injection blast passages leading to a mixing chamber and spray nozzle, a heated surface in said air passage opposite said spray nozzle, and means for injecting a mixture of fuel and gases across said air passage and onto said heated surface.

12. In a fuel injection device for an internal combustion motor, a series of valves, each having a fuel measuring chamber, there being one of these valves for each cylinder of the motor, and a vent passage common to said fuel chambers, said vent being connected to the air intake manifold of the motor.

13. In a fuel injection device for an internal combustion motor, a series of valves, each having a fuel measuring chamber, there being one of these valves for each cylinder of the motor, a vent passage common to said fuel chambers, said vent being connected to the air intake manifold of the motor, and a throttle valve between said vent passage and said manifold.

14. In a fuel injection device for an internal combustion motor, a valve having a fuel measuring antechamber, a vent passage connected from said antechamber to the air intake of the motor, and a throttle valve in said passage for regulating the flow of fuel into said antechamber by varying the pressure in said chamber.

JOHN E. FULLER.
